UNITED STATES PATENT OFFICE.

GEORGE HALINKA AND GEORGE SANTO, OF DETROIT, MICHIGAN.

DESIGN FOR A COMBINATION BRUSH, COMB, AND MIRROR.

60,615.

Specification for Design. Patented Mar. 14, 1922.

Application filed September 20, 1920. Serial No. 411,674. Term of patent 7 years.

To all whom it may concern:

Be it known that we, GEORGE HALINKA, a citizen of the United States of America, and GEORGE SANTO, a citizen of the present domain of Hungary, residing at Detroit, in the county of Wayne and State of Michigan, have invented a new, original, and ornamental Design for a Combination Brush, Comb, and Mirror, of which the following is a specification, reference being had to the accompanying drawing, forming part thereof.

Fig. 2 is a side elevation of the same.

We claim:

The ornamental design for a combination brush, comb, and mirror as shown.

GEORGE HALINKA.

GEORGE SANTO.
